(57) **CLAIM**

The ornamental design for a tower with viewing carriage tracks as shown and described.

DESCRIPTION

FIG. 1 is a front isometric view of a tower with viewing carriage tracks.

FIG. 2 is a front side elevation view thereof.

FIG. 3 is a back side elevation view thereof.

FIG. 4 is a left side elevation view thereof.

FIG. 5 is a right side elevation view thereof.

FIG. 6 is as top plan view thereof.

FIG. 7 is an enlarged view of the box 7 in FIG. 1.

FIG. 8 is an enlarged view of the box 8 in FIG. 4.

FIG. 9 is a front isometric view of a second embodiment of a tower with viewing carriage tracks.

FIG. 10 is a front side elevation view thereof.

FIG. 11 is a back side elevation view thereof.

FIG. 12 is a left side elevation view thereof.

FIG. 13 is a right side elevation view thereof.

FIG. 14 is as top plan view thereof.

FIG. 15 is an enlarged view of the box 15 in FIG. 9; and,

FIG. 16 is an enlarged view of the box 16 in FIG. 12.

The features shown in broken lines in the drawing depict environmental subject matter only and form no part of the claimed design.
